UNITED STATES PATENT OFFICE

HARRY VISSERING, OF KENILWORTH, ILLINOIS

INDICATOR FOR RADIATORS

Application filed July 29, 1921. Serial No. 488,355.

The present invention relates in general to indicators, and more particularly to indicators for automotive vehicles and one which is intended to call attention to and to indicate the state of the water contained within the radiator commonly used in connection with the cooling system of the internal combustion engine.

Among the more important objects of the invention is the provision, of a means preferably visible from the driving seat station, for rendering visible indications as to the general state of the water in the radiator, of other means giving more specific information as to the state and more particularly the temperature of the water, and the embodiment of means of the general character just indicated in a tube which forms the radiator filling opening, together with such other objects as may be hereinafter pointed out, or may appear.

In accomplishing the objects referred to and gaining certain advantages to be set forth below, I have provided the structures shown in the accompanying drawings wherein—

Figure 1 is an elevational view of one embodiment of the invention;

Figure 2 is a vertical sectional elevational view of the device of Figure 1;

Figure 3 is a horizontal sectional view taken on the line 3—3 of Figure 1;

Figure 4 is a horizontal sectional view taken on the line 4—4 of Figure 2;

Figure 5 is a vertical sectional elevational view of another embodiment of my invention;

Figure 6 is a horizontal sectional view taken on line 6—6 of Figure 5;

Figure 7 is a vertical sectional elevational view of a still further embodiment of my invention; and

Figure 8 is a horizontal sectional view taken on line 8—8 of Figure 7.

Broadly considered, the device includes a perforated casing communicating with the radiator 4 and provided with a sight opening through which the general state of the water can be ascertained, in combination with an indicator from which can be ascertained with comparative accuracy the ap-

proximate state of the water. This may be secured in the filling opening ordinarily provided in the radiator top and may serve as a tube 5 through which water is supplied to the radiator.

In the form of device shown in Figures 1 to 4, the casing, indicated generally at 10, comprises the outer tube, 11, and the transparent closure member 15. The outer tube 11 is provided with a lower screw-threaded nipple, 12, adapted to be threaded into the radiator opening 6, and as here shown is provided with a sight opening, 14, so positioned that it will be directed towards the driver.

The transparent closure member, 15, is secured in position within the tube 11 against the shoulder, 16, by the spider, 17 (secured by a set screw 17') against which spider in turn the screw threaded cap, 18, bears. Upon viewing Figure 2, it will be noted that the transparent member, 15, which is conveniently tubular in form, is closed save at its open ends, and that such ends are sealed to prevent leakage around the periphery of the tube, 15, by means of the washers, 19 and 20, interposed between the tube and the shoulder, 16, and the tube and the spider, 17, respectively. The overflow tube 27 of the radiator is, for the purposes of my invention, extended upward inside of the casing 10 to the upper portion of said casing.

In the use of the structure thus far described, it will be observed that should the water in the radiator heat up, this fact will become apparent at the sight opening, 14, by the presence of vapor or bubbles arising due to convection currents, or the precipitation upon the inside of the transparent tube of water of condensation.

It will be readily appreciated that such an emanation from the surface of the water in the radiator may be sufficient as a warning of high heat conditions, but may be inadequate to present the desired more explicit information as to the approximate temperature of the water.

To meet this situation I have, therefore, provided a second indicator in the nature of a temperature responsive element, such as a

thermometer, 21, supported between standards 22, 22, depending from the spider, 17, and resting upon the pin, 23, in the sleeve, 24, carried by the standards, 22. The thermometer is preferably centrally positioned and the gauge portion thereof (if such be used) arranged to register with the space, 25, between the standards, 22, and with the sight opening, 14. To enhance the visibility of the member, 21, and facilitate reading the same, a sight opening 14' is provided opposite the sight opening, 14, and in registry therewith.

It will be understood that the indications through the vapor, bubbles or water of condensation are in a sense indications by convection currents, whereas the thermometric indications are indications by heat conduction inasmuch as the lower portion, 26, of the thermometric device is in communication 20 with the radiator.

It is well known that upon heating a portion of liquid a vapor is given off which due to being of greater temperature than the surrounding air will rise, and in the present instance, enters the closure member thus creating convection currents which continue so long as the difference in temperature referred prevails for the reason that the heated vapor rises and the closure being cooler produces 30 water of condensation which continues the production of convection currents so that an indication as to the state of the water in the radiator is made.

With reference now more particularly to the device of Figures 5 and 6, it will be perceived that the structure herein shown although similar to that of Figures 1 and 2 differs therefrom in certain respects. Among the primary features of difference are the following: that the thermometer, 21a, is supported eccentrically of the casing, generally indicated at 10a, the upper end being loosely carried in a socket in the spider 17a and has its bulb portion supported on the pin 23a, which is carried by a sleeve, 24a, shown as integral with the screw-threaded nipple, 12a; and that in order to provide for more light and hence not only greater illumination of the interior of the casing, 10a, but also to render the indicator readable from more directions, as well as more easily, I have provided tube, 11a, with an increased number of sight openings, 14a, four thereof, spaced 90° apart being illustrated in the drawings, thus giving the tube, 11a, a spider-like cross-section clearly to be seen on reference to Figure 6. The cap 18a corresponds to cap 18 of Figures 1 and 2. The overflow tube 27a of the radiator is, for the purposes of my invention, extended upward inside of the casing 10a into the pocket 28a provided in spider 17a.

In the further embodiment of my invention shown in Figures 7 and 8, the transparent portion, 15b, of the casing generally indicated

at 10b, is fixed in position externally of the tube, 11b, instead of internally thereof, and is held in position between the washers, 19b and 20b, by means of the bearing ring, 33b, and the cap, 18b, which in the present instance, is internally threaded for engagement with the upper end of the tube, 11b. The thermometer, 21b, has its bulb portion sustained by the pin, 23b, mounted in the sleeve, 24b, preferably integral with the screw-threaded nipple, 12b, and has its upper end socketed in a boss, 34b, integral with the upper end of the tube, 11b, the function of the spiders, 17 and 17a, being performed by the bearing ring 33b. The overflow tube 27b of the radiator is, for the purposes of my invention, extending upward inside of the casing 10b to the upper portion of said casing.

Having thus described my invention and illustrated its use, what I claim as new and desire to secure by Letters Patent is—

1. In combination with a water cooling radiator having an outlet member to atmosphere, of an indicator for the radiator including an elongated casing having a transparent portion and having its lower end normally in free communication with the top of the radiator above the normal level of liquid therein, a removable spider member in said casing engaging said transparent portion, a closure member of said casing for retaining said spider and said transparent portion, said outlet member extending into said casing and having an inlet adjacent to the upper end thereof so as to cause vapor prior to its discharge to atmosphere to pass through said casing and by convection currents deposit water of condensation on said transparent portion, thereby indicating the vaporization state of the water in the radiator, and means in said transparent portion for indicating the temperature of the water in the radiator, said means being supported jointly by said spider and said casing at its ends so as to also be visible through said transparent portion. 100

2. In combination with a water-cooling radiator, of an indicator mounted thereon comprising a casing having a pair of sight openings in relative alignment, heat responsive means including a tubular thermometer in registry with said sight openings, and spaced standards between which said heat responsive means is mounted, said standards being so positioned that the heat responsive means is visible through said sight openings, and said standards having an enlarged socket portion to receive the bulb of said thermometer. 115

3. In combination with a water-cooling radiator, of an indicator mounted thereon comprising a casing having a pair of sight openings in relative alignment, heat responsive means in registry with said sight openings, and spaced standards between which said heat responsive means is mounted, said 125

standards being so positioned that the heat responsive means is visible through said sight openings, a spider for supporting said standards and in engagement with said casing.

5 4. In combination with a water-cooling radiator, of an indicator mounted thereon comprising a casing having a pair of sight openings in relative alignment, heat responsive means in registry with said sight openings, and spaced standards between which said heat responsive means is mounted, said standards being so positioned that the heat responsive means is visible through said sight openings, a spider for supporting said standards and in engagement with said casing, means for preventing rotation of said spider and standards.

5. In combination with a water-cooling radiator a device providing a plurality of indicators for showing the state of the water therein, including a casing in open communication with the radiator having apertures in transverse alignment provided with a transparent closure to form sight openings, 25 the inner surface of said transparent closure being exposed to convection currents of vapor issuing from the radiator for showing by deposition thereon of water of condensation the evaporation state of the water in the 30 radiator, and a temperature responsive element in said casing, so located as to be visible through said sight openings, for rendering a specific indication of the temperature of the water by heat conduction.

35 6. In combination with a water-cooling radiator, of an indicator mounted thereon and comprising a casing having a transparent portion normally in communication with the top of the radiator and in the path of vapor 40 issuing therefrom, said transparent portion thus permitting observance of the state of the water by emanations thereof created by convection currents and rendered visible by condensation on said transparent portion, 45 and a temperature responsive element disposed in alignment with said transparent portion and visible through the transparent portion for indicating the temperature of the water.

50 In testimony whereof I have hereunto signed my name.

HARRY VISSERING.
